John H. Miller
WITNESS:

UNITED STATES PATENT OFFICE.

GAETANO PAGANO, OF BROOKLYN, NEW YORK, ASSIGNOR OF ONE-FOURTH TO SALVATORE BENFONTI AND ONE-FOURTH TO GAETANO SOFIA, BOTH OF BROOKLYN, NEW YORK.

CLOTHES WRINGER.

Application filed March 29, 1926. Serial No. 98,279.

This invention relates to improvements in clothes wringers.

The principal object of the invention resides in the provision of a laundry appliance or clothes wringer in which the clothes are dried simultaneously with the wringing operation, so as to eliminate the hanging of clothes for drying purposes and the loss of time usually required for the drying of the same.

Another object of the invention is to provide a clothes wringer in which a heating unit is enclosed within a pair of hollow rollers, between which the clothes are passed for wringing purposes, the heat from the unit penetrating the walls of the rollers to the exterior surface thereof, so that the clothes are protected from direct contact with the unit to prevent any possibility of scorching.

With these and other objects in view, the invention resides in certain novel construction and combination and arrangement of parts, the essential features of which are hereinafter fully described, are particularly pointed out in the appended claim, and are illustrated in the accompanying drawing, in which:

Figure 1 is a side elevation of my improved clothes wringer.

Figure 2 is an elevational view of one end of the wringer.

Figure 3 is a similar view of the opposite end.

Figure 4 is a vertical longitudinal sectional view on the line 4—4 of Figure 2.

Figure 5 is a vertical transverse sectional view on the line 5—5 of Figure 4.

Referring more particularly to the drawing, the reference numeral 10 designates the support or frame of the clothes wringer and upon which are arranged a pair of spaced base bearing members 11, which receive the reduced ends 12 of a hollow roller 13. One end of the roller is closed and carries a gear 14 for meshing engagement with a driving gear 15, which latter gear may obtain its power in any suitable manner, such as from an electric motor or any manually operated mechanism. Intermediate bearing members 16 co-act with the bearing members 11 for rotatably supporting the roller 12, and which intermediate bearing members are provided with a seat for rotatably supporting a hollow roller 17, disposed

above the roller 13 and in vertical alignment therewith. The roller 17 is also closed at one end and carries a gear 18 for meshing engagement with the gear 14 of the roller 13. The roller 17 receives its rotation from the roller 13, and turns in a direction opposite to said roller.

The roller 17 is yieldingly held in engagement with the roller 13 so as to be movable toward and away from the same when the clothes are inserted therebetween for wringing purposes. The means for yieldingly mounting the roller 17 comprises a pair of top bearing members 19 which are bolted to the intermediate bearing members 16, and which members 19 are provided with slots 20 for receiving the headed end of an adjustable screw 21. Springs 22 are interposed between the head of the screw 21 and between a bearing plate 23 which rests upon the roller 17. The tension of the springs may be adjusted by means of a thumb nut 24 which co-acts with the threaded end of the screw 21, and which tension is always sufficient to hold the roller 17 in pressing engagement with the roller 13. Insertible through the open ends of the rollers 13 and 17 is a heating unit shown in its entirety as at 25, and which comprises a bracket or plate 26 constructed of an insulation material such as porcelain, and from which extends a core 27, about which a coil of wire 28 is wound. The ends of the wire extend beyond the bracket 26 and are connected with a suitable electric current.

The plate or bracket 26 is slotted as at 29 for receiving one end of a core 30, and which core extends within the roller 17. The core is provided with spaced collars 31 which snugly fit within the hollow roller, so as to hold the core 30 in spaced relation with the inner walls of the roller. A coil of wire 32 encircles the core 30 and also passes out of the outer end of the core and is connected with a source of electric current. The outer end of the core 32 carries a shield 33 for closing the slot 29 so as to prevent the escape of heat from within the hollow roller 17. The entire heating unit 25 is removably supported upon one of the sets of bearing members by screws 34 or the like.

From the foregoing description, it will be seen that I have provided a clothes wringer through which the clothes to be wrung are passed, and at the same time the clothes are

dried by reason of the heating cores which extend into the respective rollers. By slidably mounting the heating core 30 with respect to the core 27, it will be seen that the 5 roller 17 is capable of moving away from the roller 13 as the clothes pass therebetween. It will be appreciated that the gears 14 and 10 18 will always mesh, by reason of their elongated teeth when the roller 17 moves upward, and the said rollers are rotated at a relatively slow rate of speed, so that the heat from the rollers will have sufficient time to thoroughly dry the wet articles passed therethrough. Any suitable means 15 may be provided for regulating the heat of the heating coils such as a rheostat commonly used in electric appliances.

While I have described what I deem to be the most desirable embodiment of my 20 invention, it is obvious that many of the

details may be varied without in any way departing from the spirit of my invention, and I therefore do not limit myself to the exact details of construction herein set forth nor to anything less than the whole of my invention limited only by the appended claim. 25

What is claimed as new is:—

A laundry device comprising a pair of tubular rollers, one of which has rotative and bodily movements, a heating unit for 30 said rollers comprising a pair of heating cores, one each extending into said rollers, a bracket carried by one of said heating cores, and means for slidably mounting the other of said heating cores on said bracket 35 for bodily movement with said bodily movable roller.

In testimony whereof I have affixed my signature.

GAETANO PAGANO.
